UNITED STATES PATENT OFFICE.

LOUIS ROSENFELD, OF NEW YORK, N. Y.

DESIGN FOR INKSTANDS.

Specification forming part of Design No. 7,934, dated December 15, 1874; application filed November 18, 1874.
[Term of Patent 3½ years.]

To all whom it may concern:

Be it known that I, LOUIS ROSENFELD, of New York, in the State of New York, have invented a new and original Design for an Inkstand, of which the following is a specification:

The nature of my design is fully represented in the accompanying photographic illustration, to which reference is made.

My design consists of a square prism, A, having the upright corners *a* slightly beveled or chamfered, and the bottom corners *n* like-

wise beveled, but considerably more than the upright corners *a*. On the top a plain ring, *m*, rises up around the ink-well B.

What I claim as my invention is—

The design for inkstands, consisting of the square prism A, with beveled bottom edges *n*, chamfered edges *a*, and annular flange *m*, as shown and described.

LOUIS ROSENFELD.
